UNITED STATES PATENT OFFICE.

WILLIAM W. BEVAN, OF MELROSE, MASSACHUSETTS.

DESIGN FOR AN EMBOSSED PAPER DOILY.

49,137.

Specification for Design.

Patented June 6, 1916.

Application filed January 28, 1916. Serial No. 74,949. Term of patent 7 years.

To all whom it may concern:

Be it known that I, WILLIAM W. BEVAN, a citizen of the United States, residing at Melrose, in the county of Middlesex and State of Massachusetts, have invented a new, original, and ornamental Design for an Embossed Paper Doily, of which the following is a specification, reference being had to the accompanying drawing, forming part thereof.

The figure is a plan view of an embossed paper doily, showing my new design.

I claim:

The ornamental design for an embossed paper doily, as shown.

WILLIAM W. BEVAN.

Witnesses:

THOMAS F. McDEVITT,
ROBERT H. LELAND.
